UNITED STATES PATENT OFFICE.

B. A. MILLS, OF FORT WORTH, TEXAS.

AUTOMATIC LINER SAFETY.

Application filed January 19, 1926. Serial No. 82,282.

The present invention relates to an attachable safety locking device for use in linotypes or similar type-casting machines to protect mold liners; this device fastens 5 to the under side of the intermediate channel having a locking and unlocking device which moves into and out of the entrance of the intermediate channel automatically. It is supported or held in position by attachable brackets and positively overcomes 10 the damaging of mold liners by ejector blade while cams are rotating.

To the above and other ends, which will be found as the description proceeds, this 15 invention resides in the arrangements of a combination of new parts throughout and in the details of its construction, hereinafter described and claimed.

The form of this invention is illustrated 20 in the accompanying drawing, in which Fig. 1 is an interior view of the invention; Fig. 2 is a perspective view of a model of the invention connected with the under side of the intermediate channel R.

25 Referring in details to the drawing, the present invention is a preferred embodiment of steel parts, having as its essentials:

A frame 8 (Fig. 1), containing a longitudinal channel extending from bracket 15 30 to hood screw 10, through which transfer blades 2 and 4 extend. Transfer blade 2 is constructed in a sort of angular form having two fingers A and B; finger B is forced upward when finger A is released by lug 16, there being a coil spring 1 connected with a hood base screw 17 and finger A. The upward movement of said finger B brings it into engagement with lug C of a channel latch 3, raising it at F, there 35 being an interposing coil spring in wall of said channel latch 3 at E it is held in elevated position closing said channel's entrance.

40 When the vise mechanism of said type-casting machines is opened for making changes of molds or liners its trimming knife block or sector cover H is withdrawn from a sectional justification lever 5 at G leaving said justification lever free from pressure and hanging to its hinge 14 and lugs 13 and 16.

45 The said channel latch 3 having been raised in the entrance of said intermediate

channel it thereby prevents the line of matrices from going into the first elevator 55 head unless it is withdrawn when the dial lever I is properly adjusted. This obstruction being offered at S Fig. 2.

There is a long finger and delivery slide mechanism having a lower end starting 60 roller which engages a starting clutch, located on the main cams of said type-casting machines. The said cams are caused to rotate when said starting clutch is engaged by said starting roller which may contain a 65 line of matrices at its opposite end or long finger Q.

The unlocking arrangement contains a dial lever key 6 which is slotted at 9 making it adjustable, an interchangeable transfer blade 4 adapting it for use on various models. Its front end is slotted at K accommodating a channel latch screw 7 which enables said channel latch to be drawn downward by said dial lever key 6 which is also 70 operatively connected with said dial lever I which controls and changes the size of ejector blades, its lug D being engaged by dial lever key 6 when registering multiple 75 4 at I (Fig. 2).

The frame's inside wall P, N and L aligns with inner wall J of said channel latch 3 adapting it for attachment to the under side of said intermediate channel.

This invention constitutes a positive and 80 practical mold liner safety arrangement, automatic throughout. It operates by raising the ejector scale lever to size 4 and back to the size of blade wanted, this should be done before the operator sends in his first line of 85 matrices for each length or size of slug used.

Having thus described the invention I 90 claim:

In an automatic liner safety device, 95 adapted to be attached to the lower side of the intermediate channel, a channel latch located at the entrance of the intermediate channel and movable into and out of the path of the leading delivery slide finger, an interchangeable ejector dial lever key adapted to engage a lug on an interchangeable 100 transfer blade connected with the channel latch, an interchangeable justification lever movable into and out of the path of the trimming knife sector cover or block adapted to withdraw an outside transfer blade, 105

an outside transfer blade operatively connected with the justification lever and also adapted to move the channel latch to obstructing position when the vise frame is open and to move out of engagement with the channel latch when the justification lever is engaged by the sector cover or trimming

knife block in the normal locked position of the vise frame.

In testimony that I claim the foregoing 10 as my own, I have hereto affixed my signature.

B. A. MILLS.
